MAIL RECEPTACLE FOR STEERING POSTS OF AUTOMOBILES

Filed Aug. 7, 1925

Joseph Rogers Inventor

By *Paul S. Eaton*
Attorney

UNITED STATES PATENT OFFICE.

JOSEPH ROGERS, OF INDIAN TRAIL, NORTH CAROLINA.

MAIL RECEPTACLE FOR STEERING POSTS OF AUTOMOBILES.

Application filed August 7, 1925. Serial No. 48,745.

My invention relates to receptacles adapted to be attached to the steering post of an automobile, the objects being to provide a receptacle capable of holding letters and other mail matter in such a way as to render them visible at all times to the occupant of the automobile; another object of my invention is to provide easy means for the distribution of mail along rural routes, where it is desired to have the mail arranged in their box order; another object of invention is to provide a specially constructed receptacle with special fastening means, and one that can be manufactured at a very small cost, and one that will fill a long felt need among the rural mail carriers.

Having thus stated some of the objects of my invention, a brief description of the drawings will now be given in which—

Figure 1 is a perspective view of my receptacle showing it attached to the steering post of an automobile;

Figure 2 is a plan view of my device;

Figure 3 is a side elevation of my receptacle showing it attached to the steering post of an automobile;

Figure 4 is a cross-sectional view of my receptacle, looking towards the rear end.

Having thus briefly described the different figures in the drawings, a detailed description of the drawings will now be given in which like reference characters indicate corresponding parts thruout the drawings.

The numeral 1 indicates the steering post of an automobile, while the numeral 2 represents the bottom of my receptacle, which has grooves 3 and 4 therein, which fit on each side of the steering post. The numerals 5 and 6 indicate the respective sides of the receptacle, while 7 indicates the closed end. The corners of the sides are cut off as at 8 and 9.

In the bottom of the grooves 3 and 4 holes are made, and thru these holes bolts 10 penetrate. These bolts 10 also penetrate cuffs 11 on the lower side of the steering post for securing the device to the steering post in a rigid and secure manner.

The sides 5 and 6, and the bottom 2 are

preferably of one continuous piece of sheet metal, and the end 7 may also be a part of the piece out of which the device is made. The grooves 3 and 4 are stamped in the metal sheet, the corners are cut away, and the sides and end joined together as at 12 and 13 by means of soldering or other desired means, and thus constructed the device is ready to be attached to the steering post of an automobile.

The device is attached to the steering post of an automobile and then the letters or other mail matter is placed therein, and the rural mail carrier proceeds on his route. The first box to be served will receive mail from the front portion of the box, then the next patron to be served will be shown by the address on the next succeeding piece of mail matter, and thus on until the route has been served.

Thus it will be seen that I have provided a mail receptacle which will be of great service and convenience to mail carriers, one which will render the mail of any patron readily available at all times without the necessity of loosening straps or other crude devices now in use.

Having thus fully described my invention, what I desire to protect and secure by Letters Patent will be set forth in the appended claim, it being understood that I have shown only a preferred embodiment of my invention, and that structural details may be changed from time to time, so long as they fall within the scope of the appended claim:

I claim:

In a device of the class described, a receptacle having a flat bottom, two sides and one end being joined to said bottom and positioned at right angles thereto, grooves in the bottom, holes in said grooves, bolts in said holes, and means cooperating with said bolts for securing the receptacle to the steering post of an automobile.

In testimony that I claim the foregoing as my own, I have hereunto set my signature this the 23rd day of July, 1925.

JOSEPH ROGERS.
